UNITED STATES PATENT OFFICE.

HARRY C. PEFFER, OF EAST ST. LOUIS, ILLINOIS.

TARGET.

No. 925,785.

Specification of Letters Patent.

Patented June 22, 1909.

Application filed March 13, 1908. Serial No. 420,988.

To all whom it may concern:

Be it known that I, HARRY C. PEFFER, a citizen of the United States, and resident of East St. Louis, St. Clair county, Illinois, have invented certain new and useful Improvements in Targets, of which the following is a specification containing a full, clear, and exact description, reference being had to the accompanying drawings, forming a part hereof.

My invention relates to a target constructed of frangible material and adapted to be thrown into the air by a target trap of ordinary construction.

The object of my invention is to so shape and construct a target as that when the same is thrown by the trap it will take an irregular curved or spiral path of travel, this flight or movement of the target closely simulating the flight of a live bird, and offering to the marksman a target which is much harder to hit than targets of the ordinary construction, which generally travel in approximate arcs of circles, in vertical planes.

My improved target is in the shape of an inverted truncated cone, or the frustum of a cone; or a combination of cones with smooth or roughened surfaces; and is thrown from a trap in the ordinary manner, with the concave side uppermost; and the target in flight tends to turn over or to arrive at such a position as that the convex side will ride uppermost, and in so doing the target describes an irregular spiral curve, the direction of which is toward either the right or left hand, depending on the direction in which the throwing arm of the target trap moves.

To the above purposes, my invention consists in certain novel features of construction and arrangement of parts, which will be hereinafter more fully set forth, pointed out in the claims, and illustrated in the accompanying drawings, in which:

Figure 1 is a plan view of a target of my improved construction; Fig. 2 is a transverse section taken on the line 2—2 of Fig. 1, with dotted lines showing variations of the angle on which the wall or outer portion of the target may be formed; Figs. 3, 4, 5, 6, 7, 8, 9, 10, and 11, are transverse sections analogous to Fig. 2, and showing various modified forms of the target.

My improved target is constructed of hard-

ened plastic material, which is frangible, in order that it will readily break when struck by shot, and said target is preferably in the form of an inverted truncated cone, comprising the flat base 1, and the inclined wall 2. The inclination or angle on which this wall 2 is formed relative the base 1 may be varied as desired, as shown by dotted lines in Fig. 2, in order to vary the air resistance against the under side of the wall 2 when the target is in flight.

In Fig. 2 the base 1 and wall 2 are shown as being equal in thickness; and to vary the center of gravity of the target and to correspondingly vary the flight thereof, the wall 2 may be made gradually thinner toward its outer edge, as shown in Fig. 3, or said wall may be made gradually thicker toward its outer edge, as shown in Fig. 4; and to further vary the shape and change the center of gravity in these forms of the target, the base 1 may be varied in thickness.

In Fig. 5 the target is shown as having an extra heavy or thick base 1 and wall 2, the same being of equal thickness; and in Fig. 7, the wall 2 is shown as having greater thickness than the base 1; and the reverse of which construction is shown in Fig. 8.

In Fig. 6 dotted lines illustrate the manner in which the height of a target may be varied, and which construction varies the area of the exterior surface of the wall 2.

In Fig. 9 I have shown a target provided with the wall 2, constructed on two angles, with the shorter angled surface adjacent the outer edge of the target; and which construction is reversed in the form of target shown in Fig. 10.

In Fig. 11 I have shown the target in the form of an inverted frustum of a cone, the wall of which is provided with a series of annular concentric corrugations.

Targets of my improved construction may be thrown by an ordinary target trap, and in leaving the carrier or throwing arm of the trap, said targets are rotated, and in such condition travel upward at an angle relative the surface of the ground on which the trap is located.

The rotation of the target during its flight creates an air cushion on the under side of the wall 2, on one side of the body of the target, and a corresponding partial vacuum on the under side of the opposite

portion of the wall; and, as a result, the target gradually tips during its flight, and this gradual tipping movement results in the target traveling through an irregular curved 5 or spiral path for a certain distance, and at a certain point in the flight of the target the same will become inverted and continue its travel or flight in a curved path in an approximate horizontal plane, and at a different angle from the angle in which said target was projected or thrown from the trap.

Practical tests of targets constructed in accordance with my invention have proven that the irregular curved or tortuous paths 10 of travel followed by said targets depend upon the angularity of the wall 2 and the thickness thereof relative to the thickness of the base 1, all of which conditions govern the center of gravity of the target.

20 The inclination of the walls or sides of the inverted truncated cone may be varied as desired to produce different lines of flight of the target, and the thickness of the walls of the body of the target may be increased 25 or diminished at various points in order to change or modify the line of flight, or the surface of the target may be corrugated or roughened; and, therefore, I do not desire to limit myself to any given angle or thickness 30 of the wall or base of the target.

Targets constructed as herein shown and described are, when in flight, much harder to hit than are targets traveling in arcs of circles in vertical planes, and, therefore, 35 much better practice is afforded, as the marksman has no knowledge of the direction in which the target will travel when thrown from the trap, as the path of travel is curved relative to both horizontal and 40 vertical planes, and the direction of the curve being variable at the will of the operator of the trap.

I claim:—

1. As a new article of manufacture, a target 45 constructed of frangible material and comprising a base portion and a circular wall integral with said base, which wall is inclined relative to the plane occupied by the base, and which target is thrown from the trap with the circular wall uppermost. 50

2. A target constructed of frangible material and comprising a saucer-shaped body having a flat base, a circular wall integral 55 with said base and which wall is inclined relative to the plane occupied by the base, and which target is thrown from the trap with the circular wall uppermost.

3. A target constructed of frangible material and comprising a saucer-shaped body having a flat base, a circular wall integral 60 with said base and which wall is inclined relative to the plane occupied by the base, which target is thrown from the trap with the circular wall uppermost, and the base and wall forming the body of the target being of different thicknesses. 65

4. A target comprising a saucer-shaped body formed of frangible material, which body is provided with a flat base, a circular wall formed integral with the edge of the 70 disk and which wall is inclined relative to the plane occupied by the base, and the thickness of the wall of said target varying at different points, and which target is thrown from the trap with the circular wall 75 uppermost.

In testimony whereof, I have signed my name to this specification, in presence of two subscribing witnesses.

HARRY C. PEFFER.
